UNITED STATES PATENT OFFICE.

ISAAC YEARSLEY, JR., OF COATESVILLE, PENNSYLVANIA.

IMPROVEMENT IN MILLSTONE-DRESS FOR BONE-MILLS.

Specification forming part of Letters Patent No. 147,783, dated February 17, 1874; application filed May 21, 1873.

To all whom it may concern:

Be it known that I, ISAAC YEARSLEY, Jr., of Coatesville, Chester county, Pennsylvania, have invented an Improved Dress for Bone-Mills, of which the following is a specification:

The object of my invention is the effective trituration of bones by grinding-surfaces which do not become unduly heated, and which can be used for a longer period than ordinary grinding-surfaces without being impaired, and can be easily renewed by reversing the motion of the mill. I attain this object by annular grinding-plates, portions of which are shown in Figures 1 and 2 of the accompanying drawing, the said plates having a dress consisting of annular rows of quadrangular teeth *a a*, the full size of which is represented in the perspective view, Fig. 3.

The two grinding surfaces, Figs. 1 and 2, bear such relation to each other that the annular rows of teeth of the revolving plate A shall traverse the spaces between the annular rows of teeth of the fixed plate A'; hence, supposing the view, Fig. 3, to represent a portion of the fixed plate, and the revolving plate to be moving in the direction of the arrow, the cutting effect on the bones will be produced by the action of two of the four edges of each pyramidal tooth of the revolving plate, in conjunction with two edges, *x x*, of each pyramidal tooth of the fixed plate. When these cutting-edges of the teeth have become worn and un-serviceable, the motion of the revolving plate should be reversed, when a new sharp set of cutting-edges are brought into play, hence the importance of making the teeth of quadrangular shape, so as to present four cutting-edges. In order to permit this reversal of the motion of the revolving plate and still retain the triturating effect, it is essential that there should be groups of rows of teeth, the rows being parallel with each other and with a radial line passing through the center of each group. Thus the plate A' has a series of groups, *m*, of five rows in each group, the

central row of which is on the radial line *y y*, the other rows being parallel with the radial row, and all the teeth of each group being of the same size.

Angular vacancies necessarily occur between the groups *m*, and these vacancies are studded with such teeth as the spaces will permit. The dress of the plate A, Fig. 1, varies slightly from that above described, but the same rule is observed as regards groups of parallel rows of teeth, and intervening angular spaces with teeth arranged in accordance with the character of these spaces.

It will be observed that in each plate some of the teeth are removed near the inner edge, thus affording vacant spaces for admitting between the grinding-surfaces the particles of bones passing from the preparatory breaking portion of the mill, for it should be understood that the grinding-plates A and A' represent the pulverizing portion only of the mill.

I prefer to make each of the plates A and A' with teeth on both sides, so that when the teeth on one side have become defective the plates may be reversed, thereby presenting new and serviceable grinding-surfaces.

Practical tests have proved that mills with the above-described dress are free from that undue heating which is a formidable defect in ordinary bone-mills.

I claim as my invention—

The within-described annular grinding-plates, each having a dress composed of pyramidal teeth arranged in groups of rows, which are parallel with a radial line passing through the center of the group, as herein set forth.

In testimony whereof I have signed my name to this specification in the presence of two subscribing witnesses.

ISAAC YEARSLEY, JR.
